6 Claims

ABSTRACT OF THE DISCLOSURE

A hinge which is particularly well suited to use with the doors of cargo containers, truck trailers, and the like. The hinge is extremely rugged and yet permits the ready removal of a door without requirement of detachment of the hinge from the jamb or other structure to which it is secured. Although the hinge may be readily disassembled, it is tamper proof when the door is in closed position.

BACKGROUND OF THE INVENTION

Hinges of the type employed in the pivotal mounting of the doors of cargo containers, truck trailers, and similar heavy duty enclosures have not been particularly well suited to the ready removal of the doors for purpose of repair, replacement, or the like. More particularly, such hinges have heretofore typically included a bracket and a leaf pivotally secured to the bracket by means of a non-removable pin. The bracket and leaf are usually welded, or otherwise substantially permanently secured respectively to the door jamb of the enclosure and frame of the door. It will be thus appreciated that when it is desired to remove the door it is necessary to detach each hinge bracket from the jamb, or each hinge leaf from the door frame. By virtue of the substantially permanent nature of the weld, or other securing means, the detachment process is tedious and time consuming, and frequently destructive.

As an alternative to the foregoing, the bracket and/or leaf of each hinge may be removably secured to the door jamb and door frame as by means of nuts and bolts. Aside from the disadvantages accruing from the large number of nuts and bolts which must be removed in order to permit removal of the door, such removable hinges are frequently susceptible to tampering and are thus not theft proof.

SUMMARY OF THE INVENTION

The present invention is primarily concerned with the provision of a hinge which may be permanently secured to a door jamb and door frame, and which yet permits the ready removal of the door without detachment of the hinge from the jamb or frame. In addition, the hinge is tamper proof when the door is in closed position.

In the accomplishment of the foregoing, the hinge of the present invention generally includes a bracket having opposed longitudinally spaced sockets at its opposite ends with aligned side openings facing transversely inward of the bracket. The hinge also includes a leaf having a hub portion traversed by a pivot pin in rotatable relation thereto, such hub portion being disposed between the opposite ends of the bracket with projecting ends of the pin received in the sockets. In accordance with the particularly salient aspects of the invention, the side openings of the sockets enable the ends of the pins to be inserted therethrough into the sockets and to be withdrawn therethrough from the socket in the assembly and disassembly of the leaf and bracket. Retention of the pin ends in the sockets is facilitated by means of a retainer member removably secured to the bracket interior and

2

having end portions complementary to the sockets disposed in closing relation to the side openings thereof. The removable securance of the retainer member is best accomplished with a single screw or equivalent fastening means which is obstructed by the leaf in its closed position and accessible when the leaf is in its open position. Thus, when the bracket and leaf are respectively permanently attached to a door jamb and frame of a door, the door may still be readily removed without removal of the bracket or leaf from the jamb or frame. The door is merely pivoted from its closed position, wherein the screw is inaccessible and the hinge is hence tamper proof, to its open position wherein the screw is accessible. The screw is removed to detach the retainer element from the bracket whereupon the leaf is disconnected from the bracket by withdrawing the ends of the pin through the access openings of the sockets.

BRIEF DESCRIPTION OF THE DRAWING

- 20 FIGURE 1 is a fragmentary perspective view of a door pivotally connected to a jamb of a cargo container, or the like, by means of a plurality of hinges in accordance with the present invention.
25 FIGURE 2 is an enlarged sectional view taken at line 2—2 of FIGURE 1, illustrating details of the construction of one of the hinges.
30 FIGURE 3 is an enlarged sectional view taken at line 3—3 of FIGURE 1, illustrating further details of the hinge construction.
35 FIGURE 4 is an exploded perspective view of the hinge on an enlarged scale.

DETAILED DESCRIPTION OF THE PREFERRED EMBODIMENT

35 Referring now to FIGURES 1 and 2 in detail, there is shown a door 11 pivotally secured to a jamb 12 of a cargo container, truck trailer, or the like, by means of a plurality of hinges 13 in accordance with the present invention. Typically, the jamb 12 is of generally rectangular tubular metallic construction, and the door 11 is provided with a frame 14 also of generally rectangular tubular metallic construction as shown. The frame is peripherally provided with an inwardly facing channel 16 containing a sealing gasket 17, and the inner periphery of the jamb is provided with an outwardly projecting rigid seal strip 18 engageable with the gasket to provide a water impervious seal when the door is in closed position.

Heretofore, the relatively rotatable parts of conventional hinges have been secured to the jamb and door frame in a substantially permanent manner, as by means of welding, or in a semipermanent manner, as by means of bolts and nuts. Removal of the door in the former case usually entails destructive disassembly of the hinges. In the latter case, the tedious and time consuming removal of a large number of nuts and bolts is required, and moreover the door may be removed surreptitiously.

60 The foregoing difficulties are overcome by means of the hinge 13 of the present invention wherein the relatively rotatable parts are permanently secured to the jamb 12 and door frame 14, while such parts are selectively disassemblable from each other in a tamper proof manner. More particularly, the relatively rotatable parts of hinge 13 comprise a bracket 19 permanently secured to the outer face of jamb 12, as by means of welds 21, and a leaf 22 permanently secured to the outer face of frame 14, as by means of welds 23.

65 The bracket 19 is of generally L-shaped configuration including right-angularly related side legs 24, 26 having a bridging portion 27 of triangular cross-section extending across the interior angle therebetween. The bracket further includes longitudinally opposed rectangular end portions 28, 29 extending across the end edges of the side legs 24,

26 and projecting beyond the side edge of one leg 24. The projecting tips of the end portions 28, 29 are formed with opposed arcuate sockets 31, 32 having side openings 33, 34 facing transversely inward toward side leg 26. The sockets 31, 32 are preferably defined by arcuate rim walls 36, 37 in right-angular relation to the tips of end portions 28, 29 and extending substantially 180° from side leg 24 reentrantly toward side leg 26. Leg 26 is secured to the jamb 12.

The leaf 22 is rectangular and formed at one end with an angularly off-set cylindrical hub 38 having a diameter substantially equal the outer diameter of the socket rim walls 36, 37. The width of the leaf, i.e., axial length of the hub, is substantially equal the longitudinal distance between the facing ends of the socket rim walls. A coaxial bore 39 extends through the hub for traversal by a pivot pin 41, the opposite ends of which are engageable with the sockets 31, 32. More particularly, a bushing 42 of low friction, wear resistant material, such as nylon, is preferably coaxially disposed in bore 39 so as to present a suitable bearing surface for rotation of the pin therein. The opposite ends of the pin project beyond the ends of the hub for engagement in the sockets, introduction of the pin ends thereto being facilitated through the openings 33, 34. With the pin thus engaging the sockets, the hub is coaxially disposed between the ends of the socket rim walls and rotatable about the pin. The leaf is thereby rendered rotatable relative to the bracket.

In order to retain the pin in engagement with the sockets 31, 32, in a selectively disengageable manner, the hinge 13 further includes a retainer member 43 removably secured to the interior of bracket 19 in closing relation to the socket openings 33, 34. More particularly, the retainer member is preferably of L-shaped configuration including right-angularly related side legs 44, 46 having exterior faces adapted to engage the interior faces of the bracket side legs 24, 26 and a planar exterior apex face 47 adapted to engage the bracket bridging portion 27. In other words, the exterior of the retainer member conforms to the interior of the bracket. The retainer member is formed with parallel longitudinally spaced substantially rectangular end projections 48, 49. Such projections are adapted to engage the interior faces of the bracket end portions 28, 29 and define complementary closures for the socket openings 33, 34. More particularly, the tips of the projections 48, 49 are provided with arcuate notches 51, 52 extending substantially 180° in complementary relation to the socket rim walls 36, 37 so as to close the openings 33, 34.

Removable securance of the retainer member 43 to the bracket is preferably accomplished by means of a screw 53 traversing a bore 54 through the member normal to face 47, and threadably engaging a tap 56 provided in the bracket bridging portion 27. With the retainer member thus secured to the bracket, it will be appreciated that the pin is retained in the sockets. Moreover, it will be noted that when the door 11 is in closed position, the screw 53 is obstructed by the leaf 22 and cannot be removed. The hinge 13 of the present invention is thus tamper proof and the door cannot be surreptitiously removed. However, when the door is open, the screw of each hinge is accessible such that the retainer member can

be readily removed to permit disassembly of the leaf 22 from the bracket 19, and thus removal of the door.

I claim:

1. A hinge comprising a bracket having opposed longitudinally spaced sockets at its opposite ends with aligned side openings facing transversely inward of the bracket, a leaf having a hub portion disposed longitudinally between said sockets, a pin traversing said hub in rotatable relation thereto and having projecting ends engaging said sockets, said ends of said pin translatable through said side openings, a retainer member having end portions complementary to said sockets disposed in closing relation to said side openings thereof, and fastening means removably securing said retainer member to said bracket.

2. A hinge according to claim 1, further defined by said bracket having a generally L-shaped configuration including first and second right angularly related side legs, said brackets having end portions extending across the end edges of said side legs with tips projecting right angularly beyond the side edge of said first side leg, said tips having longitudinally opposed walls extending arcuately from said first side leg reentrantly toward said second side leg to define said sockets with side openings, said retainer member being of generally L-shaped configuration having an exterior conforming to the interior of said bracket, said end portions of said retainer member having arcuate notches in complementary relation to said walls and closing said openings.

3. A hinge according to claim 2, further defined by said leaf being rectangular and said hub being cylindrical and angularly offset from one end thereof, said hub having a diameter substantially equal to the outer diameter of said walls and a length substantially equal to the longitudinal distance between said walls, said hub having a coaxial bore traversed by said pin.

4. A hinge according to claim 3, further defined by a bushing of low friction wear resistant material coaxially disposed in said bore and traversed by said pin.

5. A hinge according to claim 3, further defined by said bracket having a triangular bridging portion extending across the interior angle between said side legs, said retainer member having a planar apex face conformably engaging said bridging portion, said bridging portion having a tap extending normally thereinto, said retainer member having a bore aligned with said tap, said fastening means comprising a screw extending through said bore of said retainer member and threadably engaging said tap.

6. A hinge according to claim 5, further defined by a bushing of low friction wear resistant material coaxially disposed in said bore of said hub and traversed by said pin.
